UNITED STATES PATENT OFFICE.

EMMA BANKOW, OF NEW YORK, N. Y.

HAIR-FRAME.

1,201,794.

Specification of Letters Patent. Patented Oct. 17, 1916.

Application filed March 22, 1916. Serial No. 85,811.

To all whom it may concern:

Be it known that I, EMMA BANKOW, a citizen of the United States, and a resident of the borough of Manhattan, city, county, and State of New York, have invented certain new and useful Improvements in Hair-Frames, of which the following is a specification.

This invention relates to improvements in hair frames, particularly for use in arranging ladies' hair, the object of the invention being to provide such means with the use of which a comparatively small amount of hair may be attractively arranged in such manner, as to give to the same an appearance of abundance, without resorting to the artificiality of switches of false hair or the like. These switches as is well known are expensive, unsanitary, and in the majority of cases, because of the lack of oils, etc., supplied to the natural hair are either originally, or become in time a poor match to the natural hair, both as to luster and color, with the resultant unattractive effect.

The present invention therefore is intended to obviate these difficulties, and at the same time provide a substitute which may be effectively concealed, light in weight, cool and sanitary and inexpensive and simple to manufacture.

A further object is to provide such a device which may be used with facility and may be adjusted for the accommodation of different thicknesses of hair, in a manner as not to break or pinch the hair.

With these and other objects in view, my invention is shown in the accompanying drawings, and will be hereinafter more fully described with reference thereto, and finally pointed out in the claims.

In the accompanying drawings: Figure 1 shows my invention placed upon a lady's head before the hair is arranged to conceal the same, Fig. 2 is a top view of the same, Fig. 3 is a side view thereof, and Fig. 4 is an end view.

Similar reference characters indicate corresponding parts throughout the several figures of the drawings.

Referring to the drawings, and more particularly to Figs. 2 and 3 thereof, my invention comprises a frame formed of wire of suitable size and resiliency, and covered with cotton, silk or other such thread to give the same a color closely assimulating that of the hair. A single length of wire is first

bent into the form of an oval 10, the end portions 11 and 12 overlapping at 13 and being twisted about each other in a single relatively long twist, are first turned about the oval portion at 14 and 15 and are then carried diagonally as at 14' and 15' and then parallel from the points 11', 12' in an arch over the length of the oval, the ends being secured by twisting the same about the end of the oval as at 16, these twists 16 filling the space between the said ends, and preventing relative movement thereof.

A transverse and rearwardly extending reinforcing shaping and supporting member 17 is secured at each side of the oval by twisting at 18 and 19, and is connected intermediately to the portions 11 and 12 by twisting thereabout at the points 11' and 12', the said portions diverging in one direction from the transverse member and being parallel in the other direction, the parallel portions being relatively longer than the diagonally extending portions. The side connecting portions of the member 17 have a curved shape of less degrees than the arch of the ends 11 and 12. A locking member 20 is secured to the parallel portions. This locking member is preferably formed as shown, of a piece of wire doubled upon itself, hingedly and slidably secured at one side and hooked over the other side by means of a hooked end 21. This locking member it will be noted, may be unhooked as shown in dotted lines in Fig. 4, or it may be slid to any position desired along the parallel portions. There is a slightly resilient connection between the locking member and the parallel portions so that it remains fixed in any position of adjustment.

As thus constructed the hair-frame comprises in its principal features the border 10, which is preferably in oval form, outwardly curved longitudinal bars 11 and 12 with diverging extensions 14' and 15' disposed apart from each other and connecting opposite ends of said frame and the cross-brace 17 connected to said border at the upper part of said frame and to said bars at the lower part thereof. The hair frame may also be defined as composed of two semi-sections disposed apart from each other and both composed of a single piece of wire, one section consisting of a curved wire 10 at one side of the frame together with the outwardly bent wire 12 and the other section consisting of the corresponding curved

border wire taken in connection with the outwardly curved wire 11. These sections are connected at the lower end of the frame by the integral uniting twist 13 and at the upper 5 end of the frame by the twist 16. The cross-brace 17 being connected to the upper and lower portions of the frame forms a downward loop adapted to engage the hair at a point below the center of the frame, thereby 10 permitting the natural hair which passes through the slot between the bars 11 and 12 to fall gracefully from the frame.

In operation the frame is placed upon the lady's head in the desired position as indicated in Fig. 1, the locking member being either unhooked or slid to the end of the parallel portions 11 and 12, whereupon the hair is brought between the said parallel portions. The locking member is then hooked and slid 20 into contact with the hair, thereby securely supporting the frame in position. The hair is then suitably arranged over the frame, in the well-known manner. The contraction of the hair inclosing space is such, it will be 25 noted, as to firmly grasp the hair by a pressing action, but in such manner as to have no pinching or breaking effect thereon.

I have illustrated a preferred and satisfactory form of my invention, but it is obvious 30 that changes may be made therein within the spirit and scope thereof as defined in the appended claims.

I claim:

1. A hair-frame comprising a border, outwardly curved longitudinal bars disposed 35 apart from each other and connecting opposite ends of said frame, and a cross-brace connected to said border at the upper part of said frame and to said bars at the lower part 40 thereof.

2. A hair-frame comprising a border, outwardly curved longitudinal bars disposed apart from each other and connecting oppo- 45

site ends of said frame, a cross-brace connected to said border at the upper part of said frame and to said bars at the lower part thereof, and a connecting member between said bars. 50

3. A hair-frame comprising a border, outwardly curved longitudinal bars disposed apart from each other and connecting opposite ends of said frame, a cross-brace connected to said border at the upper part of said frame and to said bars at the lower part thereof, and a slidible clasp connecting said 55 bars.

4. A hair-frame comprising a border, outwardly curved longitudinal bars disposed apart from each other and connecting opposite ends of said frame, and a cross-brace connected to said border at the upper part of said frame and to said bars at the lower part thereof, said bars diverging from the point of connection of said transverse brace to the lower end of the frame. 60

5. A hair-frame consisting of two sections disposed apart from each other and composed of a single piece of wire, said sections being connected at one end of said frame by a transverse twist of the border wires of said 70 sections and by two longitudinal outwardly bowed bars integral with said twist and provided at the other end of said frame with individual twists forming a transverse connection between said sections at said end, and 75 a transverse brace connected with said sections at the upper part of said frame and with said longitudinal bars at the lower part thereof.

In testimony, that I claim the foregoing as 80 my invention, I have signed my name in presence of two subscribing witnesses.

EMMA BANKOW.
